UNITED STATES PATENT OFFICE.

JOHN A. SEEDE, OF SCHENECTADY, NEW YORK, ASSIGNOR TO GENERAL ELECTRIC COMPANY, A CORPORATION OF NEW YORK.

ELECTRIC-FURNACE REGULATOR.

Application filed February 4, 1920. Serial No. 356,193.

To all whom it may concern:

Be it known that I, JOHN A. SEEDE, a citizen of the United States, residing at Schenectady, county of Schenectady, State of New York, have invented certain new and useful Improvements in Electric-Furnace Regulators, of which the following is a specification.

The present invention relates to electric furnace control apparatus, and it is the object of the invention to prevent disturbances to electric furnace operations, particularly in arc furnaces.

Arc furnaces commonly contain at least one movable electrode the arcing relation of which to another electrode is regulated by suitable control apparatus responsive to the current in the furnace circuit. When the arc in the furnace becomes unduly lengthened the operating current decreases as a consequence and this decrease sets into motion the control apparatus to shorten the arc.

It sometimes happens that the current is decreased due to some cause external to the arc and in that case the regulating apparatus may cause the electrode to come into contact with the charge. Other causes may prevent the regulating apparatus from maintaining a suitable length of arc. Contact between a carbon electrode and the charge may have a very deleterious effect, particularly when the charge consists of a bath of steel which readily combines with carbon.

In accordance with my present invention contact between the movable electrode and the charge constituting the co-operating arc electrode is prevented by providing the regulating apparatus with means rendering the same inoperative when the arc voltage falls below a predetermined value.

The accompanying drawing illustrates diagrammatically one embodiment of my invention applied to a single arc furnace.

Referring to the drawing, an arc furnace is diagrammatically indicated by dotted rectangle 1. The co-operating electrodes 2, 3, are connected by supply conductors 4, 5, to the secondary windings 6 of a transformer, the primary 7 of which is connected by conductors 8 to a source of alternating current, not shown in the drawing. The electrode 2 is shown as a movable electrode and usually consists of carbon or graphite, and commonly the stationary electrode 3 at the base of the furnace is constituted by the charge

in the furnace, such, for example, as a bath of iron or steel. The electrode 2 is fed toward the bath at a suitable rate to compensate for electrode consumption.

An electric motor 9 is mechanically connected to the electrode 2 by any form of suitable gearing, the drawing showing a speed reducing gear 10 driven by the motor acting on a nut 11 on the screw-threaded rod 12 to raise and lower the electrode. The electric motor 9 is controlled by suitable switches hereinafter described, to raise or lower the electrodes in response to variations of current in the supply circuit. For this purpose a contact making magnet 13 is connected to the secondary 14 of a current transformer, the primary of which is constituted by a portion of the supply conductor 4. The armature of this magnet is connected to a switch lever 14 operating to make contact with either conductors 15 or 16 leading to suitable contactors. An adjustable resistance 17 is connected across the winding of the magnet 13 in order to enable the setting of the magnet to be varied at will. In circuit with conductor 15 is a contactor 18 connected to the armature of a voltage controlled magnet 19 which is connected adjacent the furnace across the conductors 4 and 5 and in shunt to the arc between the electrodes 2 and 3.

The cycle of operation is as follows, assuming electrodes 2 and 3 to be in contact when a run is started.

When the transformer is energized, the magnet 19 pulls up its armature and bridges the contacts 20 in the circuit 15, and the magnet 13 also pulls up its armature and completes a circuit from the conductors 24, 16 and 25 to energize the contactor magnet 26, and cause it to pull up its armature, thereby closing the contacts 27 and 28. The circuit of the motor armature 9 is now energized through the conductors 25, 29, 30, 31 and 32, a resistance 33 being included in series, and the furnace electrodes are separated by the motor to strike an arc. When the arc is of predetermined length, the armature 14 leaves the upper contact, thereby arresting the hoist of the electrode 2.

Should the arc become too long the current becomes reduced sufficiently to cause the armature 14 to engage with the lower contact 35 thereby energizing the contactor magnet 36, current being supplied from the

mains 22, 23 through the conductors 24, 15, 37 and 25. When the contactor magnet 36 raises its armature the contacts 38, 39, are closed and the motor is energized to rotate 5 in the reverse direction through the conductors 25, 37, 31, 30, 40 and 32, lowering the electrode. When the motor is energized to lower the electrode two resistances 33, 41, are included in series as in this case 10 gravity assists the motor. The field 42 of the motor is constantly energized through the conductors 43. Both when raising and lowering the electrodes the motor 9 is brought quickly to rest by dynamic braking, 15 the resistance 44 being connected across the motor armature by the magnet 45, the closure of the contact 46 being assisted by a spring 47. When the motor circuit is closed through the resistance 44, a mechanical interlock 48 prevents the closure of the magnets 26 and 36.

Should the electrodes be lowered too far for any reason, unduly shortening the arc and causing the voltage drop in the arc to 25 fall below the value for which the relay 19 is set, then the armature 18 will drop out and open the circuit of the relay magnet 36 and prevent continued lowering of the electrodes. As soon as the arc lengthens by 30 burning away of the electrode 2, or other causes, and the voltage drop across the arc increases to the voltage for which the magnet 19 has been set, the contactor 18 again closes and the above described regulation 35 is resumed.

Ordinarily the regulation of the position of the electrode 2 with reference to the charge will be adjusted by the operation of the control mechanism, while the contacts 40 20 in the circuit 15 remain closed, the relay 19 being set to open the circuit 15 at an arc voltage below the usual operating range.

Should the supply circuit voltage for any 45 reason decrease unduly, the operating current will fall correspondingly and the control mechanism will cause the electrode 2 to be lowered correspondingly in accordance with the setting of the current responsive 50 magnet 13. Finally the arc voltage may be reduced to a point for which the magnet 19 has been set to open. This will prevent further lowering of the electrode 2. When 55 the line voltage again increases and with it the line current, the control mechanism is

free to raise the electrode 2, as the circuit of the conductor 16 to the raising magnet 26 has remained closed. The usual operation of the furnace, therefore, can be resumed at once.

60

While I have explained and illustrated my invention with reference to the operation of a single phase arc furnace, I wish it to be understood that it may be applied to the regulation of a furnace of a different 65 number of phases, and that the character of the furnace may be otherwise varied without departing from the spirit of my invention.

What I claim as new and desire to 70 secure by Letters Patent of the United States, is.—

1. A regulating apparatus for an electric arc furnace having co-operating electrodes, comprising a furnace circuit, means 75 for feeding at least one of said electrodes toward the co-operating electrode to maintain an arc, and means for rendering said feeding means inoperative when the voltage between said electrodes falls below a 80 predetermined value, while the supply voltage in said furnace circuit is as great as a said value.

2. A regulating apparatus for electric furnaces having electrodes adapted to support an electric arc comprising a furnace supply circuit, an electric motor operatively connected to at least one of said electrodes, means for controlling said motor to adjust the position of said electrodes in response 85 to variations of current in said supply circuit and means for de-energizing said control means when the voltage between said electrodes falls below a predetermined value while the voltage in said supply circuit remains above said value.

3. A regulating apparatus for an electric furnace having paired, relatively movable electrodes comprising a supply circuit, motor means for moving at least one of said electrodes, means for controlling said motor means in response to an electrical condition in said circuit, and a circuit breaker arranged to deenergize said control means and having an operating coil connected in 100 shunt to a single arc between said electrodes.

In witness whereof, I have hereunto set my hand this 3rd day of February, 1920.

JOHN A. SEEDE.
